UNITED STATES PATENT OFFICE

FRED E. JOHNSON, OF LA CROSSE, WISCONSIN

CHRISTMAS-TREE HOLDER

Application filed January 8, 1929. Serial No. 331,042.

This invention relates to the class of supports or holders and pertains particularly to an improved and attractive means for holding Christmas trees in upright position.

5 The primary object of this invention is to provide a device for supporting trees or similar bodies in upright position which will automatically operate when the end of the tree is placed therein, to grip the tree and 10 hold it as positioned.

Another object of the invention is to provide a device of such character that when the tree or other article held thereby is pulled upwardly the supported article will be immediately released.

The invention will be best understood from a consideration of the following detailed description taken in connection with the accompanying drawing forming a part of this 20 specification, with the understanding, however, that the invention is not confined to any strict conformity with the showing of the drawing but may be changed or modified so long as such changes or modifications 25 mark no material departure from the salient features of the invention as expressed in the appended claims.

In the drawing:—

Figure 1 is a view of a toy house showing 30 a tree in position in the chimney thereof;

Figure 2 is a vertical sectional view of the house chimney showing the holding device embodying the present invention, therein;

Figure 3 is a sectional view taken trans- 35 versely of the chimney substantially upon the line 3—3 of Figure 2.

Figure 4 is a detailed plan view of the joint between the tree supporting arms.

The holding device embodying this invention is designed to be used in association with a decoration which usually forms one of the decorative features of a Christmas tree such for example as the toy house 1, the holding device being adapted to be secured in the 45 chimney 2 of the house, the chimney forming a casing for the holder and for the lower portion of the tree.

If desired the house may be provided with suitable electric lights upon the interior and 50 the windows with transparent or semi-trans-

parent coverings so that the house may be illuminated while the tree is in use and when this is done it is desirable that a convenient outlet such as that indicated by the numeral 3 be placed in the house structure as for example in the roof adjacent the chimney so that current may be conveniently supplied to lights and other electrical ornaments upon the tree.

The tree holder comprises a pair of square 60 frames 4 and 5 each of which is made up of four members 6 formed of a pair of arms arranged in right angled relation and each terminating at its free end in an inwardly directed ear 7. These angled members are 65 positioned each in a corner of the chimney 2 of the building so that the ear at the end of each arm is brought into spaced relation at the central portion of a side wall of the chimney with the ear of an adjacent arm 70 and as is shown the frames are arranged one in the upper portion and one in the lower portion of the chimney.

Pivotedly positioned between the ears of each of the four pairs of each of the frames 75 4 and 5 is one end of a pointed dog 8 and the dogs carried by the upper frame 4 are pivotedly connected with the underlying dogs carried by the lower frame 5 by the toggle arms 9 so that movement of the dogs 35 carried by one frame will cause a corresponding movement of the dogs carried by the other frame.

Each of the dogs 8 carried by the lower frame or the frame 5, has pivotedly connected thereto as at 10, the point where a toggle arm 9 is connected, a short depending link 11 the lower end of which is pivotedly attached as at 12 to one of the four arms 13 of a platform indicated as a whole by the numeral 14. This platform 14 is preferably constructed of a pair of members made up of two arms arranged in right angled relation the two members being flattened and joined together by a suitable bolt 15 at the point of joinder of their arms. The arms of the platform member are of such length that the links 11 which connect them with the adjacent dogs 10 are directed inwardly at their lower ends.

From the foregoing it will be seen that 100

when the platform 14 is raised the links 11 will be straightened out to a certain extent and the dogs 8 and connecting toggles 9 will be raised and will swing apart each moving 5 toward the adjacent side of the chimney body 2. Sufficient room is thus provided for the insertion of the lower or butt end of a tree such as indicated by the numeral 16 and it will be seen that when the tree is inserted 10 between the dogs which are pointed inwardly and upwardly from each side wall of the chimney and is brought to rest upon the platform 14 and allowed to bear down thereagainst the platform, links and dogs will all 15 be lowered until the points of the dogs are brought into engagement with the body of the tree.

Application of additional downward pressure to the tree will result in the penetration 20 of the dogs into the tree body from all sides and the tree will be firmly clamped and remain in upright position when released.

It is clear that in order to release the tree to remove it from position it is only necessary 25 to pull upwardly thereon whereupon the dogs will be caused to swing upwardly and will extract themselves from the tree body.

Having thus described my invention what I claim is:—

30 1. A supporting device for an upright body, comprising a frame designed to surround the body, a plurality of pairs of ears carried by and projecting inwardly of said frame, a plurality of arm members each pivotally attached to said frame between a pair of ears and disposed to be directed toward a common center, a support for the body, and link members connecting the support with said arms to suspend the same therefrom, the 35 application of the body to the support bringing the free ends of said arms into engagement with the body.

2. A support for an upright body, comprising a frame made up of a plurality of sections, each having its ends turned to form an ear and each having its ears in spaced relation with ears of adjacent sections, pointed arm members each pivotally mounted between a pair of ears and directed toward 40 the center of the frame, links each pivotally attached at one end to an arm adjacent the free end thereof, and a body supporting platform suspended beneath the arms by and pivotally attached to said links.

55 3. A support for an upright body, comprising a frame made up of a plurality of sections, each having its ends turned to form an ear and each having its ears in spaced relation with ears of adjacent sections, pointed 45 arm members each pivotally mounted between a pair of ears and directed toward the center of the frame, links each pivotally attached at one end to an arm adjacent the free end thereof, a body supporting platform comprising a pair of substantially V-shaped 50

members secured together at their apices, and a pivotal connection between each of the arms of the platform at the outer end thereof, and a link member.

4. A support for an elongated body to 70 maintain the same in upright position, comprising a housing, a frame conforming to the outline of the housing and designed to fit therein made up of a plurality of members each formed to provide a pair of ears, said members being arranged in forming the frame to position each ear in spaced relation to the ear of another member, pointed arms each pivotally mounted between a pair of ears and having its free end directed toward the center of the frame, a body supporting platform, and link members pivotally connecting the platform with said arms to suspend it therefrom, each of said links having one end attached to the arm adjacent its free end.

85 In testimony whereof I hereunto affix my signature.

FRED E. JOHNSON.
